[57] ABSTRACT

A multi-hull vessel having a grid for launching and retrieving watercraft supported between its sterns. A method for launching and retrieving watercraft from the vessel by ballasting the sterns down to immerse the watercraft-carrying grid and de-ballasting the sterns up to the normal operating draft.

SEMI-SUBMERSIBLE TENDER

BACKGROUND OF THE INVENTION

The present invention pertains to ships for launching or retrieving various types of watercraft such as lighters, barges or small boats.

In the prior art one type of ship for picking up another ship is illustrated in U. S. Pat. No. 2,375,139. The ship shown therein has a boat well into which an auxiliary boat is floated and then ballasted down to rest on the boat well. Such a system requires that the boat to be retrieved have ballast tanks. The ballast tanks may be inappropriate for many types of watercraft in that they add undesired size and expense to the cost of the watercraft to say nothing of operating characteristics.

Another system for picking up barges onto a ship is illustrated in U. S. Pat. No. 3,572,274 wherein the stern portion of the hull supports an inflatable and submersible pontoon for movement between a loading position in which the pontoon is floated or submerged in water in a stowed position in which the pontoon is located above the water surface. When the pontoon is moved to launching position, it is submerged in water and the barge is towed into the loading zone above the submerged pontoon. The pontoon is thereupon inflated so that the upper surface engages the bottom portion of the barge and seaway compensating devices are operated to lift the pontoon to its stowed position while the barge is coupled or attracted to the pontoon, for example, by way of electromagnets. Such a system for picking up barges requires extensive equipment for inflating and deflating the pontoon, moving it to a stowed position, moving it to a launching position and for operating electromagnets.

Yet another ship of the prior art is described in U. S. Pat. No. 3,587,505. The ship described therein is limited to loading and unloading in smooth water by the low tunnel through which barges enter the vessel. For practical purposes this limitation restricts it to loading and unloading in protected places. Such limitation might be acceptable for a cargo carrier, but it would make the ship unsuitable for supporting small craft at sea. This vessel is shown with its cross structure always in the water which is an inefficient shape even on smooth water. Waves could therefore be expected to cause a substantial loss of speed.

SUMMARY OF THE INVENTION

The present invention overcomes these and other disadvantages of the prior art by providing a multi-hull vessel having a platform for launching and retrieving watercraft suspended from the vessel between the hulls at a location above the normal waterline of the vessel. The vessel is adapted to selectively submerge at least a portion of the platform for launching and retrieving watercraft. In operation watercraft carried on the grid are launched by ballasting the vessel down by its sterns until the platform is sufficiently submerged to immerse the watercraft to a draft which will support flotation; releasing the watercraft from the platform and floating it free; and ballasting the sterns of the multi-hull vessel up to their normal draft. The watercraft are retrieved by reversing the procedure.

No alterations in the structure of the watercraft need be made in order to launch and retrieve them from the vessel. Also, the vessel has no extensive, costly equipment for launching a watercraft, only ballast tanks and

5 a fixed grid, equipped if necessary with cradles to fit the type of craft being handled. The amount of ballast required for launching and retrieving a watercraft is kept within reasonable limits because of the small waterplanes of the connecting struts.

The tender described herein can load or discharge a small craft in seas large enough to induce some motions in the craft being handled, and can carry out these operations while under way at a low speed. The tender, 10 with its clean hulls and great clearance, can maintain nearly full speed in rather high waves.

It is an object of the invention to provide a marine vessel capable of launching and retrieving watercrafts.

15 It is another object of the invention to provide a vessel for launching and retrieving watercraft while underway.

It is still another object of the invention to provide a vessel for launching and retrieving watercraft which requires no alterations to the watercraft.

20 It is yet another object of the invention to provide a vessel for picking up watercraft entirely out of the water for maintenance and other purposes.

DESCRIPTION OF THE DRAWINGS

25 FIG. 1 is a perspective view of the multi-hull vessel of the invention.

FIG. 2 is a side view of the vessel with its sterns ballasted down.

30 FIG. 3 is a side view of the vessel carrying a watercraft.

DESCRIPTION OF THE PREFERRED EMBODIMENTS

35 Referring now to FIG. 1, the improved marine vessel of the present invention comprises an above water portion 10, a pair of submerged, buoyant members 12 and 14, a pair of connecting struts 16 and 18, and a watercraft-carrying grid 20. Shown in FIG. 1, the above water hull portion 10 is configured as a boat tender 40 while it may be generally of practically any shape. Underwater members 12 and 14 comprise a pair of elongated buoyant displacement bodies or members which may have a cylindrical or non-cylindrical shape. Each buoyant member is surmounted by a connecting strut.

45 Struts 16 and 18 are made buoyant and have a length comparable to that of submerged members 12 and 14, but either may be longer than the other. The maximum beam of struts 16 and 18 is less than the beam of corresponding submerged members 12 and 14. The waterplane area of struts 16 and 18 is less than the maximum horizontal area of submerged members 12 and 14 for minimizing the amount of ballast required to ballast the sterns with the vessel down as discussed in detail below.

55 Connecting struts 16 and 18 unite above water hull portion 10 and submerge buoyant members 12 and 14 into a floatable, marine vessel.

60 Connecting grid 20 is a fixed grid structure shown in FIG. 1 between the after ends of the connecting struts 16 and 18. Grid 20 is positioned between the struts above the normal operating waterline of the multi-hull vessel. The grid must, of course, have sufficient strength to carry a watercraft of a desired size which may be one boat or more weighing as much as several hundred tons each. The grid itself may be a simple grating, but preferably, it has cradles designed to receive a particular type of based craft such as, for example, cra-

dles 22 and 24 which are adapted to receive watercraft 26.

Each submerged, buoyant member and corresponding strut includes ballast tanks, such as for example, ballast tanks 28, 30, 32 and 34. Each submerged member also includes a compartment 38 for fuel and a compartment 36 for machinery for propelling the vessel.

Launching a watercraft from the vessel is accomplished by the following method. The multi-hull vessel is ballasted down by its sterns until the grid 20 is sufficiently submerged to immerse the watercraft 26 to a draft which will support flotation. Watercraft 26 is next released from grid 20 or, if not restrained, it simply floats free. After the watercraft 26 floats free of grid 20, the sterns of the multi-hull vessel are ballasted up to their normal operating draft of the vessel.

The method of launching a watercraft from the vessel may be carried out while the vessel is under way, preferably proceeding slowly into the prevailing waves. The multi-hull vessel is ballasted down by its sterns until at least a portion of grid 20 is submerged. Dragging the after end of above water portion 10 creates a slick over the cradles 22 and 24 of grid 20 which will be somewhat smoother than the surrounding area of the sea. Control by the watercraft 26 over its horizontal position with respect to the sterns of the multi-hull vessel and with respect to cradles 22 and 24 of grid 20 is established by steering the self-propelled watercraft 26 in the current passing through grid 20.

Retrieving a watercraft onto the multi-hull vessel is accomplished by the following method. The multi-hull vessel is ballasted down by its sterns until at least a portion of grid 20 is submerged to a depth greater than the draft of the watercraft to be retrieved. Watercraft 26 is then maneuvered over grid 20. Watercraft 26 is moored to the vessel while it is floating in a position over at least a portion of submerged grid 20. The watercraft 26 is then retrieved onto grid 20 by ballasting the sterns of the multi-hull vessel up to their normal operating draft.

Watercraft 26 may be retrieved while the vessel is underway. The self-propulsion and steering capabilities of the watercraft 26 are used to maneuver it in the current passing through grid 20 to control its horizontal position relative to the sterns of the vessel and to cradles 22 or 24 of grid 20. Watercraft 26 is then moored to the vessel and landed on grid 20 and retrieved by deballasting the sterns of the multi-hull vessel up to their normal operating draft.

The above-described methods of launch and recovery are especially suited to the type of double-hull vessel shown in the drawings because the small water-planes of the multi-hull vessel keep the required amount of ballast within reasonable limits. However, a vessel with double-hulls of more conventional shape can also be used.

I claim:

1. A marine vessel comprising:
  - a. A pair of submerged elongated buoyant members in a predetermined spaced relation including forward and aft ballast tanks for selectively varying the draft and trend of said vessel;
  - b. An above water hull portion in juxtaposition with said pair of submerged buoyant members;
  - c. A pair of elongated substantially vertical connecting struts, each said strut affixed to a corresponding submerged buoyant member and to said above water hull portion for uniting said pair of buoyant members and said above water hull portion into a floatable marine vessel; and
  - d. A platform comprising a grid permitting water to flow therethrough whereby having minimized lift, for launching watercraft from said marine vessel and for retrieving watercraft thereto, said platform affixed to said marine vessel between said pair of connecting struts in a location above the normal waterline, and selectively capable of at least partial submergence by trimming said vessel with said ballast tanks.
